9044X

PATENTED AUG. 20, 1835.

J. FALES.
MACHINE FOR SERVING ROPE OR RIGGING.

James Fales, New Bedford, Massachusetts

Letter's Patent

The Schedule referred to in these Letters Patent and making part of the same, containing a description in the words of the said James Fales himself of his invention in a machine for serving Ropes or Rigging.

To all persons to whom these presents shall come. James Fales of New Bed-
ford in the County of Bristol and Commonwealth of Massachusetts Wishes me-
thority to Greet - Be it known that I the said James Fales have in-
vented constructed and applied to use a new and useful machine called a ma-
chine for serving Ropes and Rigging which is shaped in this way following
viz. Upon a horizontal frame or bracket of timber moving upon Rollers, is
erected a perpendicular frame to support the working part of the machine.
At a convenient height from the floor a cog wheel with a hollow or tubular
shaft or axle is attached to the aforesaid perpendicular frame. This wheel is
made in two parts, or pieces, one of them being two thirds, or three fourths,
of the whole circle, and cast with the shaft or axle attached firmly to it.
The remaining portion is moveable so that it may be taken out to ad-
mit the rope intended to be served into the hole or tube and again
reduced to its place, when it may be secured by means of cones, gibes,
or any other simple contrivance. The tube should be of sufficient diam-
eter to admit a rope of any size proposed to be served. Upon this shaft
or axle and behind the frame is placed a reel containing thread upon
which the serving yarn is to be wound and also a driving mallet. Be-
tween the reel and mallet may be placed screw or springs to operate upon
the reel by friction or otherwise in such a way as to prevent its revolving faster
than the yarn can be used upon the reel. The mode of operation of this
machine is as follows. It being ^{best} stretched taut in a horizontal po-
sition and securely fastened. The machine is brought where the rope can be passed
through the tube in the wheel abovescribed the yarn from the reel is then
passed around the rope and mallet in the usual manner and motion being

given to the wheel either by a crank directly opposite or otherwise by the interposition of another wheel and when the work is very accurately and expeditiously performed. And the said James Fales claims to be the inventor of the above described combination of machinery, and its application to the purpose of Scoring Paper, or Clipping. Testimony that the above is a true specification of my said machine as above described I this day unto set my hand this twenty first day of March in the year of our Lord One thousand eight hundred and thirty five.
